UNITED STATES PATENT OFFICE.

SIEGFRIED HELD, OF CHICAGO, ILLINOIS, ASSIGNOR TO THE HELD COMPANY, OF CHICAGO, ILLINOIS, A CORPORATION OF ILLINOIS.

WATER-STERILIZING TANK.

1,085,578.

Specification of Letters Patent.

Patented Jan. 27, 1914.

Application filed April 18, 1913. Serial No. 762,019.

To all whom it may concern:

Be it known that I, SIEGFRIED HELD, a subject of the Emperor of Austria-Hungary, residing at Chicago, in the county of Cook 5 and State of Illinois, have invented certain new and useful Improvements in Water-Sterilizing Tanks, of which the following is a specification.

This invention relates to improvements in 10 a tank and apparatus used for sterilizing water by means of ozone, and it consists in certain peculiarities of the construction, novel arrangement and operation of the various parts thereof, as will be hereinafter 15 more fully set forth and specifically claimed.

The primary object of the invention is to provide simple and efficient means for thoroughly purifying or sterilizing, by 20 means of ozonized air, large quantities of water as the same passes from a supply pipe to a reservoir or retaining receptacle, in which the sterilized water may be kept until it is desired for use, and from which reservoir it may be conducted by means of suitable 25 pipes to the desired places for consumption.

Another object is to provide means whereby every particle of the volume of water which passes through my improved sterilizing tank will be aerated or charged with ozonized air, to the end that sterilization of the water will be absolute or perfect and accomplished in the most rapid and thorough manner.

35 Other objects and advantages of the invention will be disclosed in the subjoined description and explanation.

In the accompanying drawing, which serves to illustrate an embodiment of the invention—the figure is a central vertical sectional view through the tank and apparatus, showing the parts assembled in the positions they will occupy when ready for use.

The reference numeral 1 designates the 45 tank, which may be of any suitable size, form and material, but preferably cylindrical in shape, as shown, and has its upper and lower ends tightly closed by means of heads 2 and 3 respectively. The upper head 50 is detachably secured to the tank by means of bolts and nuts 4, and the lower head is preferably secured to the lower end of the tank by being riveted thereto. Each of the heads 2 and 3, is by preference outwardly convexed, and each has a central opening.

Located in the opening of the upper head 2, is a pipe section 5, which extends downwardly into the tank and has secured to its lower end, by means of a screw collar 6, a screen 7, of wire cloth or other suitable 60 material.

Connected to the upper end of the pipe 5, by means of a suitable coupling 8, is a supply pipe 9, which leads from a source of water supply (not shown). The opening in 65 the lower head 3, has communication through a pipe 10, secured to said head, with a reservoir (not shown), in which the sterilized water may be stored for use.

Located in the lower portion of the receptacle is a horizontally disposed frame, which consists of a number of beams 11, of I-beam construction, which are supported at their outer ends by means of brackets 12, secured to the inner surface of the tank. Resting 70 on the upper surface of the supporting frame comprising the I-beams 11, is an annular trough 13, which has a centrally disposed and upwardly extended hollow neck 14, on the upper portion of which is supported an annular flange 15, on the upper portion of another annular trough 16, the inner wall of which is upwardly tapered, as is clearly shown. Resting on the upper surface of the annular flange 15, is a similar flange 17, of another annular trough 18, which is of the same construction as the trough 16, except that it is of less diameter. An upper annular trough 19, having a central cavity or cup 20, which cup extends into the upper portion of the neck 14, rests on the upper portion of the flange 17, of the trough 18. Each of the troughs 16, 18 and 19, is provided in its lower portion with a number of openings 21, for the passage of 75 water, and the said openings 21, in the trough 16, communicate with small pipes 22, extended downwardly from the lower part of the trough 16, to near the bottom of the trough 13, and are employed for the purpose 80 to be presently explained.

Extended through the upper portion of the vertical wall of the tank is a pipe 23, which leads from a supply of ozonized air (not shown), and has communicating therewith within the tank a series of branch pipes 24, 25, and 26, which are extended downwardly within the troughs 19, 18 and 16 respectively. Each of the branch pipes 24, 25 and 26 has communication at its lower end 105 110

with and supports a tubular ring 27, which rings are located in the lower portion of the troughs just above named, and each of said rings is provided with numerous openings 28, in their lower parts. Extended from the air supply pipe 23, downwardly, and into the lower portion of the tank, and then upwardly, is another branch pipe 29, for the supply of ozonized air to the trough 13, or 5 lower trough. The portion of the branch pipe 29, which extends upwardly within the tank is also located in the neck 14, of the trough 13, and has an extension 30 extended through the wall of the neck 14, and downwardly into the trough 13, near the wall of 10 said neck. The lower end of the branch pipe 30, communicates through suitable couplings 31, with a plurality of tubular rings 32, which are located concentrically with respect 15 to one another within the trough 13, just below the lower ends of the tubes 22, which lead from the trough 16 into the lower part of the trough 13. Each of the tubular rings or pipes 32, is provided with numerous perforations 33, in its lower portion for the escape of ozonized air. Leading from the 20 air supply pipe 23, is another branch pipe 34, which is extended into the coupling 8, of the water supply pipe, and has connected 25 to its portion within said coupling a branch pipe 35, which extends downwardly within the pipe section 5, to near the lower end thereof.

From the foregoing and by reference to 30 the drawing, it will be understood and clearly seen that by admitting water to the tank through the supply pipe 9, and pipe section 5, and that by opening the valve 36, in the air supply pipe 23, which valve controls 35 the supply of ozonized air, which may be under pressure, water and air will be simultaneously supplied to the tank, in which operation it is evident that as the water passes the lower end of the branch pipe 35, 40 suction will be created in said branch pipe, thus causing the air to mingle with the water, which will rise in the cup 20, and overflow the top of the same into the trough 19, from which it will pass through the 45 openings 21, in the bottom thereof into the trough 18, and from thence through the openings 21, in the last named trough into the trough 16, and from thence through the 50 openings 21, and tubes 22, in the last named trough into the bottom trough. In its passage 55 from the upper trough to the lower one, it is obvious that the ozonized air passing from the various rings 27, will impregnate or aerate the water, and that further aeration 60 will take place in the lower trough 13, by reason of the air escaping through the perforations in the tubular rings 32, within said trough.

65 It will be noted that the trough 13 has no

openings in its bottom, and consequently the entire volume of water admitted to the tank will have to pass from the upper trough and from thence and the intermediate troughs into the lower one, from which it will overflow at its outer periphery and pass out through pipe 10, to the reservoir or storage receptacle. As the lower trough 13 has no outlet it is obvious that the water must overflow the rim of said trough in order to pass 70 therefrom, and as the small pipes or tubes 22 are extended from the trough 16 to near the bottom of the trough 13, it is manifest that the water passing through said tubes from the trough 16, will be discharged near the 75 bottom of the trough 13 and in close proximity to the perforated tubular ring 32, so that the water thus discharged will be thoroughly impregnated with ozonized air or aerated.

While I have shown my invention in its 80 preferred form, yet it will be evident that various parts can be changed considerably from the structure and description given without departing from the spirit of the invention, and for this reason I do not wish to 85 be limited to the exact structure shown and described.

Having thus fully described my invention, what I claim as new and desire to secure by Letters Patent is—

1. The combination with a tank having an inlet for water in its upper portion and an outlet therefor in its lower part, of a plurality of superimposed channeled members located in the tank and provided with means 100 for the passage of water therefrom, and a separate perforated tubular member located in each of said channeled members and having communication with a supply of ozonized air.

2. The combination with a tank having an inlet for water in its upper portion and an outlet therefor in its lower part, of a plurality of superimposed channeled members located in the tank, at least one of said members having perforations in its lower part 110 for the passage of water therefrom, a separate perforated tubular member located in at least one of the channeled members above the lowermost one, and a separate perforated 115 tubular member located in the lower channeled member, all of said tubular members having communication with a supply of ozonized air.

3. The combination with a tank having an 120 inlet for water in its upper portion and an outlet therefor in its lower part, of a plurality of superimposed channeled members located in the tank, at least one of the channeled members having perforations in its 125 lower part for the passage of water therefrom, a perforated tubular member located in at least one of the channeled members above the lowermost one, and a series of perforated tubular members located in the 130

lower channeled member, all of said tubular members having communication with a supply of air under pressure.

4. The combination with a tank having an inlet for water in its upper part and an outlet therefor in its lower portion, of a plurality of superimposed channeled members located in the tank, the lowermost of said channeled members being imperforate in its lower part but having its outer wall located in a lower horizontal plane than its inner wall, the channeled member located above and adjacent to the lowermost one having perforations in its lower part, a series of tubes located in said perforations and extended downwardly into the lowermost channeled member, a perforated tubular member located in at least one of the channeled members above the lowermost one, and a perforated tubular member located in the lowermost channeled member near the lower end of said tubes, all of said perforated tubular members having communication with a supply of air.

5. The combination with a tank having an inlet for water in its upper portion and an outlet therefor in its lower part, of a horizontally disposed supporting frame located in the lower portion of the tank, an annular channeled member mounted on the supporting frame and having a tubular central wall projected above its outer wall, an annular channeled member having a centrally disposed hollow portion extended downwardly and into the upper portion of the tubular wall of the first named channeled member, an annular channeled member interposed between the upper and lower channeled mem-

bers and supported by the tubular wall of the latter, a perforated tubular member located in at least one of the upper channeled members, and a perforated tubular member located in the lower channeled member, all of said tubular members having communication with a supply of air.

6. The combination with a tank having an inlet for water in its upper portion and an outlet therefor in its lower part, of a plurality of superimposed channeled members located in the tank, all of said channeled members except the lower one having openings in its lower portion for the passage of water, and a perforated tubular member located in each of said channeled members and having communication with a supply of ozonized air.

7. The combination with a tank having a common inlet for air and water in its upper portion and an outlet therefor in its lower part, of a plurality of superimposed channeled members located in the tank, at least one of the channeled members located above the lower one being provided with perforations in its lower part for the passage of water therefrom, a perforated tubular member located in the uppermost channeled member and in each of said members interposed between the uppermost and lowermost one, and a series of perforated tubular members located in the lower channeled member, all of said tubular members having communication with a supply of ozonized air.

SIEGFRIED HELD.
